UNITED STATES PATENT OFFICE.

ALBERT R. GOLDRICK, OF CLEVELAND, OHIO.

ELECTRICAL SWIVEL CONNECTER.

Application filed November 1, 1920. Serial No. 420,944.

This invention relates to new and improved electrical connectors, adapted for attaching electrical cords carrying a plurality of conducting wires to movable devices using electric current. This invention is intended for use where such cords are attached to electric flat irons, massage machines, and similar devices which are moved about when in use.

10 An object of the present invention is to provide means in connection with an electrical conducting cord of more than one wire, whereby the cord wires may be relieved from strain consequent to the repeated bending 15 and twisting incident to the use of portable electrical appliances, and which quickly results in destruction of the wire or connection.

Another purpose of my invention is to 20 provide means whereby a plurality of electrical conductors may be maintained in conductive contact in an electrical connection, while permitting a universal angular movement of the cord terminal means.

25 My invention may be embodied in a variety of constructions, a few of which I have set forth in the accompanying drawings, and the invention is hereinafter more fully described in connection with these drawings, 30 the essential characteristics being summarized in the claims.

In the drawings Fig. 1 is a side elevation of my invention as used for a plug connection to a flat iron; Fig. 2 is a cross section 35 of Fig. 1 substantially along the line 2—2 of Fig. 1; while Fig. 3 is a cross section of the same view substantially along the line 3—3, and Fig. 4 is a cross section of Fig. 1 along the line 4—4 of Fig. 3; in Figs. 5, 6, 40 and 7, I have shown variations of the swivel construction which may be as conveniently used as the swivel construction shown in Fig. 2, while Fig. 8 shows the approximate relation of the swivel plug and flat 45 iron when the former is connected to the latter; Fig. 9 is a cross sectional view taken through the device at right angles to the section shown in Fig. 3; Fig. 10 is a cross sectional view of the modified construction shown in Fig. 5 taken at substantially right angles to the section shown in Fig. 5; Fig. 11 is a cross section taken substantially along the line 11—11 of Fig. 6.

Describing the drawings by the use of reference characters, in Fig. 1, I have shown 55 a pair of plug body members 2 and 3, composed of any suitable insulating material having cavities 4 with spherical surfaces at the inner ends thereof. A pair of cord terminal insulating members 5 and 6, having 60 enlarged ends with spherical surfaces and adapted to loosely fit the cavity 4 of the plug body members 2 and 3, are shown as constituting the movable end of the device.

In Fig. 3, I have shown the flat iron plug 65 connections 7 and 8, which may be constructed of any conductive spring material of low resistance. Incorporated with these contacts are the swivel strips 9 and 10, which may be constructed of the same material. 70 These strips, which are punched near the inner ends to form the pivot bearings 11 and 12 as shown in Figs. 2 and 3, are adapted to act as a clamping means for holding metallic angle pieces 13 and 14, which are oppositely located on the pivot bearing support 15, and serve to maintain these angle pieces 75 upon the support.

Co-operating with the angle pieces 13 and 14 are a pair of cord terminal conductors 80 16 and 17. The inner ends of these conductors are formed in a manner similar to the punched ends of the conductors 9 and 10, the punched portions being arranged to fit openings formed in the angle pieces 13 85 and 14, as shown in Fig. 2. The pivotal axis of the conductors 16 and 17 is substantially 90° from the pivotal axis of the conductors 9 and 10.

In order to maintain the support 15 in 90 proper relative position to the plug body members 2 and 3, the ends may be curved or circumferential; the axis of these surfaces being 90° apart and coincident with the pivotal axes of the conductors 9, 10 and 16 and 95 17. These ends are adapted to abut complementary surfaces formed in the plug body members 2 and 3, and the terminal insulating members 5 and 6.

The angle pieces 13 and 14 have punched 100 bearing portions 41 which are adapted to fit snugly into the holes 18 and 19 in the support 15, while the inside diameters of these punched portions are adapted to receive the punched portions located near the ends of 105 the conductors 16, 17, and 9, 10. Located

in the plug body members 2, 3, 5 and 6 are the curved surfaces 202 and 212, which are complementary to the surfaces on the bearing support 15, and as the swivel is turned 5 in any angular position within the external limitation of the insulation members these radial surfaces will permit the movement of the insulating members without at any time dislocating the center of the bearing support 10 15. This arrangement also serves the purpose of maintaining this center in its proper relation to the position of the conducting members when the plug is being connected and is adapted to take up any pressure which 15 might otherwise distort the swivel joint. When the plug is disconnected there is a pull or tension on the members 5 and 6, which fit the inner surface 4, and this stress is thereby taken up by the insulating members 20 and is not transmitted through the swivel center.

In order to insure smooth rubbing surfaces between the plug body members, I have provided the screws 20 and 21, which may be of 25 such size as to act as dowel pins, as well as a binding means for retaining the various members in position.

Located at the outer end of the insulating members 5 and 6, I have provided a goose-neck extension which serves to increase the 30 leverage action on the swivel center and greatly decreases the possibility of the wire twisting or breaking at the connecting point 28.

35 In Fig. 5, in which I have shown a variation in the construction of the swivel, the plug body members may be quite similar to those shown in Figs. 1 and 3. The conducting means, however, is constructed so as to 40 form contacting swivel surfaces, which take the form of concentric spherical surfaces. The outer connection, which is composed of the members 24 and 25, serve as one conductor, while the inner sphere composed of 45 the members 26 and 27 serve as the other conductor. These spherical members may be properly spaced and insulated by means of the hollow insulating cylindrical members 28 and 29, which serve to space the tubular 50 shanks 30 and 31, and 32 and 33. By constructing the swivel in this manner the cord terminals may have a turning movement as well as a universal angular movement. This turning movement may act to 55 relieve the torsional strain on the cord wires due to the twisting of the same.

In Fig. 6, I have shown another variation of the swivel construction, in which a pair of spherical contact surfaces are formed to provide a swivel conducting means for the conductors as shown at 34, 35, 36 and 37. In order to prevent the members from sliding out of contact or to prevent their movement in a direction which would cause a short 65 circuiting, I have provided the punched por-

tions 38, which are adapted to slide radially of the center of the spherical surfaces, and be confined in the radial slots 40 as shown in Fig. 7. The modified constructions shown in Figs. 5 and 6 may have plug body members which are assembled in the same manner as the plug body members illustrated in the construction shown in Fig. 1.

70 From the foregoing description of an embodiment of my invention it is readily understood that by the use of the same in conjunction with portable electrical appliances much annoyance and inconvenience is eliminated by the prevention of frequent breaks or short circuits occurring in the connecting 75 cord.

Having thus described my invention, I claim:

1. In a device of the character described, the combination of a pair of articulated 80 members and a plurality of conductors carried by each member, each of said members being separable into half portions having cavities formed therein, wherein said conductors may lie with the adjacent ends in overlapping electrical contact, said contacting portions being arranged relative to the articulated members in such a manner as to permit the universal angular movement of the articulated members.

2. In a device of the character described, the combination of a pair of members joined in a hollow ball and socket connection, a plurality of conductors carried by each member, the member comprising in part the 100 socket of said connection being longitudinally separable into half portions having cavities formed therein wherein conductors may lie with their ends extending into the said hollow connection and in overlapping 105 electrical contact with the ends of conductors carried by the other member, said contacting portions being arranged relative to the ball and socket joint in such a manner that universal angular movement of the members 110 is permitted.

3. In a device of the character described, the combination of a pair of members joined in a hollow ball and socket connection, a plurality of conductors carried by each 115 member, one member being longitudinally separable into half portions having cavities formed therein wherein conductors may lie with their ends extending into the hollow ball and socket connection and in overlapping 120 electrical contact with the ends of conductors carried by the other member, said contacting portions being articulated about the center of rotation of the ball and socket joint whereby universal angular movement 125 of the members is permitted.

4. In a device of the character described, the combination of a pair of members joined in a hollow ball and socket connection, a plurality of conductors carried by each mem- 130

ber, both members being longitudinally separable into half portions having matched cavities formed therein wherein conductors may lie with their ends extending into the 5 hollow ball and socket connection and in overlapping electrical contact with conductors adapted to carry current of like polarity, said contacting portions being arranged relative to the ball and socket joint in such a manner that universal angular movement of 10 the members is permitted.

In testimony whereof, I hereunto affix my signature.

ALBERT R. GOLDRICK.
